UNITED STATES PATENT OFFICE.

BARTOW B. YOUNMANS, OF COLLEGE PARK, GEORGIA.

TELEGRAPH-KEY.

1,109,310.

Specification of Letters Patent.

Patented Sept. 1, 1914.

Application filed April 4, 1913. Serial No. 758,978.

To all whom it may concern:

Be it known that I, BARTOW B. YOUNMANS, a citizen of the United States, residing at College Park, in the county of Fulton and State of Georgia, have invented a new and useful Telegraph-Key, of which the following is a specification.

The present invention relates to improvements in telegraph keys, one object of the present invention being the production of a simplified construction of horizontally swinging lever key, in which the movement of the lever in one direction produces "dots", while the movement of the lever in the other direction produces "dashes", there being provided an equalizing resilient means for maintaining the lever normally out of contact and in line open condition.

A still further object of the present invention is the provision of a key of this character which is designed to displace the usual vertically movable key and to be attached to the usual support or table top in place thereof, the same being very simple and compact in construction and being provided with terminal screws that form a means for fastening the key base to the table top or desk and at the same time forming a connection for the main line.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings: Figure 1 is a side elevation of the complete key showing the same attached in position to a support, as a table or desk top. Fig. 2 is a top plan view of the complete key. Fig. 3 is a sectional view adjacent the lever supporting frame showing the detail construction thereof and a modified means for maintaining the lever in open circuit position. Fig. 4 is a detail view 50 of the damping device used for preventing

the vibration of the lever and sending a "dash."

Referring to the drawings, the numeral 1 designates the top of a table or desk which is the usual support for transmitting keys, there being disposed thereupon an insulating base 2 with the metal base 3 of the key, the two bases 2 and 3 being properly clamped to and secured upon the support 1 by means of the screws 4 and 5 and thumb nuts 4' and 5' respectively. These screws constitute the binding or terminal posts for the respective main line conductors 6 and 7 and are electrically connected with the parts of the key, as will presently appear so that telegraphic signals such as "dot" and "dash" may be sent out upon the line. Connected to the base plate 3 and upstanding therefrom, adjacent one end, is a supporting frame 8 which has disposed therein for horizontal swinging movement the shaft 9 adjustably connected by means of the screw 9' to the connecting portion of the frame 8 while the lower end thereof is mounted within the base plate 3. Pivoted connected to the shaft 9 for horizontal swinging movement is the rigid section 10 of the horizontally disposed swinging lever of the key. The free end of the portion 10 is reduced as at 11 to fit within the recessed end of the finger piece 12, the same being preferably made of vulcanite or some such material to provide a non-conducting gripping portion for the manipulation of the key.

In order to hold the lever in open circuit condition, so that the same will assume the position as shown in Fig. 2, the upper terminal spring 13 is connected fast to one face of the frame 8 and has its terminals disposed to bear resiliently upon the adjacent portion of the section 10 of the lever at equidistant points from the shaft 9, the advantage being that when the finger piece 12 is released, the spring will automatically return the lever to circuit open position.

Carried by the frame 8 opposite to the spring 13 and also projecting in opposite direction to the finger piece 12, is a stud or arm 14, in which is threaded the adjusting screw 15, the inner end of which is disposed

to be in a path to abut the solid portion 10 of the lever in a line substantially with the engagement thereof with the outer terminal of the spring 13, the screw 15 being adjustable so as to limit the movement of the lever when the same is being manipulated to send a "dot" out upon the line. Connected to and upstanding from the base 3 and approximately in a line with one terminal of the frame 8 adjacent to the end of the base, is a post 16, which has disposed in the upper end thereof the adjustable screw 17, whose contact terminal 18 is disposed in a path to be engaged by the fixed contact 19 of the lever when the lever is manipulated to send a "dash" out upon the line. A post 20 is also connected to and upstanding from the base 3 intermediate of the ends thereof and upon the same side of the lever as the post 16, there being a conductor 21 extending from the upper end of the terminal screw 4 to the post 20 and finally to the post 16, a conductor 22 being connected upon the upper end of the terminal post 5 to the base 3, and as the respective posts 16 and 20 are insulated from the base 3, a circuit is thus completed through the contacts 18 and 19 when the lever is manipulated to send a "dash" or by means of the "dot" adjusting screw 30 mounted in the upper end of the post 20 and the contact end 29 of the "dot" sending spring 28. As in these forms of transmitting keys, a resilient section is provided, said section being shown as at 23 having its terminals connected respectively to the section 10 and section 25 of the lever, the section 25 being slotted as at 24 so as to accommodate one terminal of the spring 28 and also the section 23 therebetween. The section 25 as clearly shown is provided with exterior threads 26 upon which is mounted the milled adjustable weight 27, which provides means whereby the lever may be adjusted to varying "touches" of the manipulators.

In order to provide a means for resiliently holding the lever against vibration when the finger piece 12 is moved to cause the contacts 19 and 18 to engage and thus send out upon the line a "dash", a support 32 is connected to the base 3 adjacent the free end of lever and has pivoted to the upper end thereof, the L-shaped pendant 33, which normally assumes the position, as shown in Fig. 4, to be swung to the dotted line position and contacted by the cylindrical portion 25 of the lever.

From the foregoing description, it is evident that a key constructed in accordance with the present invention, may be readily attached and used in lieu of the usual vertically swinging key, and not necessitate the liability of misadjusting the usual key now employed when various operators using a horizontal key connect and discon-

nect the same from such vertically swinging key.

What is claimed is:—

1. A telegraph key including a base having two main line connecting and supporting screws for permanently connecting the base to a support, a frame carried by the base, a horizontally swinging lever supported from the base, a resilient "dot" contact spring and a fixed "dash" contact carried by the lever, two contact carrying posts connected to the base, said posts being disposed adjacent to the respective contact spring and fixed contact of the lever, and resilient means carried by the frame for equalizing the pressure at the pivotal point of the lever to maintain the lever with the contacts disengaged and the circuit open. 70 75 80

2. A telegraph key including a base having two main line connecting and supporting screws for permanently connecting the base to a support, a frame carried by the base, a horizontally swinging lever supported from the base, a resilient "dot" contact spring and a fixed "dash" contact carried by the lever, two contact carrying posts connected to the base, said posts being disposed adjacent to the respective contact spring and fixed contact of the lever, and a double terminal spring carried by the frame 85 90 95 and having its terminals disposed to engage the lever equidistantly upon each side of the pivotal point thereof.

3. A telegraph key including a base, two connecting and supporting screws connected thereto for permanently connecting the base to a support, said screws also forming the terminals for the main line, a frame carried by the base, a horizontally swinging lever supported from the base and provided with an intermediate resilient section capable of flexing horizontally, a resilient "dot" contact spring connected adjacent to the resilient section with the outer rigid section, a "dash" contact carried by the rigid section 100 105 110 upon the opposite side of the pivotal point of the lever to the resilient contact, two posts connected to and insulated from the base, one of said posts being disposed adjacent to the fixed contact while the other post is disposed adjacent to the resilient contact, an adjustable contact mounted in each of said posts, and a double terminal spring carried by the frame and having its terminals disposed to engage the lever equidistantly upon each side of the pivotal point thereof. 115 120

4. A telegraph key, including a base having two main connecting screws, a frame carried by the base, a horizontally swinging lever supported from the base, a resilient "dot" contact spring and a fixed "dash" contact carried by the lever, two contact carrying posts connected to the base, said posts being disposed adjacent to the 125 130

respective contact spring and fixed contact of the lever, and a double terminal spring carried by the frame and having its terminals disposed to engage the lever equidistantly upon each side of the pivotal point thereof.

In testimony that I claim the foregoing

as my own, I have hereto affixed my signature in the presence of two witnesses.

BARTOW B. YOUNMANS.
